METHOD OF KNITTING

Robert H. Lawson, Pawtucket, R. I., assignor to
Hemphill Company, Central Falls, R. I., a corporation of Massachusetts

Application February 19, 1935, Serial No. 7,248
In Canada November 24, 1934

3 Claims. (Cl. 66—107)

This case deals with a particular method of drawing knitted stitches when both the needles and sinkers are given simultaneous movements for the purpose of forming a stitch. The case

5 has to do especially with a particular method of timing the action of both needles and sinkers so that full benefit of the conjoint action of needles and sinkers will be realized. One purpose of this particular method of timing is to form each stitch 10 individually without disturbing any stitch or stitches which have been drawn previously, another to impose a minimum of strain upon the yarn which is being operated upon by the knitting instrumentalities.

15 In the drawings:

Fig. 1 is a somewhat diagrammatic view showing several needles and sinkers in their relative positions as they are forming loops at the knitting point, certain cams are shown in section;

20 Fig. 2 is an enlarged view of a needle, sinker and sinker jack such as are used for drawing stitches in the manner disclosed in this case;

Fig. 3 is a plan view showing a few needles and sinkers such as have been shown in Fig. 2; and

25 Figs. 4, 5, and 6 are sectional views, greatly enlarged, showing progressive steps of the forming of a stitch; for purposes of clearness, the fabric which is already upon the needles is not illustrated.

30 It has long been realized that certain advantages could be gained if both the needles and sinkers of circular knitting machines could be used to draw knitted stitches with a combined stitch drawing movement. In general, this

35 method consists in moving the needle downwardly as is the usual practice, and at the same time, moving the sinker or similar instrumentalities upwardly or at least in the opposite direction of that in which the needle was moved. With 40 the mechanism herein shown and described it was possible to actually knit fabric on a production basis and to make fabric which was superior to the usual product of circular knitting machines. However, a new problem presented itself, this

45 problem being peculiar to machines such as that disclosed herein where each knitted loop is formed by the combined and substantially simultaneous movement of needles and sinkers. This problem involved the timing of the cooperating 50 needle and sinker movements. Yarn breakage caused by strain on the same as it was being kinked into permanent loops was a factor which seriously impaired the efficiency of the machine until this peculiar timing with its advantages was 55 discovered. After the adoption of the needle and

sinker timing as herein described yarn breakage and cutting at the sinkers has been practically unknown.

Referring to Fig. 1 a series of sinkers 1 are shown spaced between a plurality of latch type needles 2. These needles and sinkers are cooperating to draw knitted stitches of a yarn 3 which is being fed in the proper relation to said needles by a yarn guide indicated at 4. It is not necessary that the needles be of the latch type 10 although latch needles are used in this case for purposes of illustration. The needles are provided with butts 5 at their lower ends which engage cams 6 and 7 to be guided thereby in their 15 yarn taking and stitching drawing movements. The sinkers, better shown in Fig. 2, have nibs, throats and stitch drawing edges which are of somewhat conventional form and each sinker extends rearwardly to terminate in a butt 8 which, in cooperation with certain cams (not shown), 20 give the sinker its radial movements. Each sinker is adapted to be swung about a pivot point 9 by means of a sinker jack 10 which engages a projection 11 on each sinker. Each jack has two offset lugs 12 and 13 which thru their engagement with projection 11 serve to control the 25 movement of the sinker in exact accordance with the contour of cams 14 and 15 which engage butts 16 on the jacks. While it is not necessary, the jacks are preferably arranged to slide within the 30 same tricks in which the needles slide and outside of said needles.

Referring to Fig. 4 there are shown portions of four needles and three sinkers. Needle 17 is in its lowermost position while the sinker 18 is in its 35 uppermost position and the stitch which has been drawn by this needle and sinker is completely formed and will suffer no further distortion or change in form except to be slightly relieved as to the tension therein by a small upward movement of the needle accompanied by a cooperating downward movement of the sinker, also of slight extent. Needle 19 has also been drawn downwardly by cam 6 until it has reached its extreme lower position. However, sinker 20 which has 40 cooperated in the drawing of the stitch which extends between sinkers 18 and 20, held in the hook of needle 19, is not yet at its uppermost elevation. This sinker will be raised a slight amount until it reaches the same elevation to 45 which sinker 18 was raised, Fig. 5, whereupon the stitch will be completed.

In theory, the timing of needle 19 and sinker 20 which are herein taken for example might be such that needle 19 would reach a bottom point 55

of cam 6 and sinker 20 would reach the uppermost extent of its travel at precisely the same time; such a method of timing would be ideal. Due to the impossibility of obtaining perfection 5 in the mechanism which has been shown, it would not be mechanically possible to realize this ideal condition. If one were to attempt such a method of timing it would be found that certain sinkers would closely approach the ideal which was being 10 aimed at, while those remaining would probably vary slightly on either side of the condition desired so that some would lag behind the needles while others would precede their cooperating needles and would reach their uppermost position 15 before the needles reached their lowest position. It has been found that this last condition is one which can not be tolerated, and to make such operation of sinkers with respect to their needles impossible, the timing has been modified 20 to make each needle descend to its lowermost point before the corresponding sinker has quite reached its highest elevation.

The next needle 21 will then engage the yarn prior to this last movement of sinker 20 but there 25 will be no particular disadvantage experienced since the yarn may be very easily drawn through the hook of one needle. If the opposite should prevail, i. e., needle 19 be forced to descend slightly after sinker 20 has reached its upper- 30 most position it would be necessary for that needle to reeve yarn over sinker 20 and also through the hook of needle 21. It is this last condition which was responsible for imposing excessive strain upon the knitting yarn and break- 35 ing the same very frequently as it was drawn over the top of said sinker.

Fig. 6 illustrates a step slightly farther in advance wherein sinkers 18 and 20 and needle 19 have continued on with their completely drawn 40 loop and have probably started to relieve the tension of that loop slightly. Needle 21 has descended and sinker 22 has risen until it is now in contact with the yarn which is coming from the supply. It can be seen from this figure 45 that the needle has made more than half of its stitch drawing movement at this time, and that the sinker will make the greater part of its upward movement after it has engaged the yarn and also draw much the greater portion of the 50 yarn which enters into the loop. The cycle will be continued with respect to needle 21 and sinker 22, the needle reaching its lowermost position prior to complete elevation of the sinker. While the needle engages the yarn first, it has an easier 55 movement than the sinker so that in the actual formation of a stitch the sinker does a greater portion of the work and does it in a smaller time interval.

In Fig. 1 the needle butts 5 may be seen descending under the action of cam 6 in Fig. 1 and the butts 16 of sinker jacks 10 may be seen in that same figure as they are moved upward more abruptly by cam 14. It is necessary to so position these cams 6 and 14 that the jack which 65 raises the cooperating sinker for any particular needle will not quite reach the tip or highest point on cam 14 as the corresponding needle reaches the extreme lower point of cam 6. The surface 14' of the sinker jack cam has a slight downward 70 slope so that the sinkers may slack off slightly for relieving the tension of stitches which have been drawn. Cam 7 is provided with a surface 7' which functions after the needles have reached their lowest position under the action of cam 6, 75 to raise those needles just enough to relieve

stitches thereon. These means for relieving stitches may be used separately or in conjunction with one another.

In the foregoing description it has been stated that the ideal condition would be for the needles, 5 such as the needle 19 and the companion sinkers or other instrumentalities such as 20, to complete their stitch drawing movements in opposite directions at substantially the same time, but that complete realization of this condition was practically impossible and that a completion of the upward movement of the sinker or other instrumentality such as 20 prior to the completion of the downward movement of the companion needle 19 resulted in yarn breakage. It is also stated 15 in the foregoing description that in order to overcome breaking of the yarn, the upward movement of the sinkers, such as illustrated by 20, Fig. 4, is delayed or retarded to lag behind the extreme downward movement of the companion 20 needle 19 in advance of said sinker 20. The retarding of the upward movement of the sinker as just described, avoids the breaking of the 25 yarn.

While the simultaneous completion of the 25 movements of the sinkers and companion needles would be desirable, the retarded movement of the sinkers to permit their companion needles to complete their drawing of the stitches before the 30 said sinkers are completely elevated, imposes less strain upon the yarn (the final drawing of the 35 stitch by the further downward movement of the needle being effected while the companion sinker such as 20, Fig. 4, is at a lower level as compared with the sinker 18 shown at the right 40 of the said needle 19, Fig. 4) than would be the case if the sinker and needle complete their stitch drawing movements at substantially the same time.

The invention has been described relative to a 40 particular embodiment of the mechanism which has been employed, but it is not intended to create the impression that the invention is limited in such respects as it is the principle involved, the concept of timing to obtain a successful 45 operation of both needles and sinkers to draw 50 stitches, which it is desired to protect. The invention is not to be limited except by the scope of the appended claims.

I claim:

1. A method of drawing stitches by the cooperative movements in opposite directions of needles and other instrumentalities such as sinkers, including a downward or other movement of a needle, drawing yarn from the source of supply 55 before the sinker-like instrumentality engages the yarn, continuing the movement of the needle in the same direction as before and moving the sinker-like instrumentality in a direction opposite to the direction of movement of the needle, 60 the last mentioned movement of the needle being substantially less than the movement of the sinker or other instrumentality during which movements of the needle and sinker-like instrumentality the yarn is engaged and drawn both 65 by the needle and by the sinker-like instrumentality although the amount of yarn drawn by the needle is materially less than the amount of 70 yarn drawn by the sinker or other instrumentality.

2. A method of drawing knitted loops by the 75 conjoint action of needles and sinkers moving in opposite directions and drawing yarn from a source of supply, each stitch being substantially completed prior to the start of drawing the next 80

succeeding stitch, each needle being timed to reach its extreme position slightly in advance of the cooperating (succeeding) sinker reaching its extreme extent of travel in the opposite direction.

5 3. A method of drawing knitted loops by the conjoint action of needles and cooperating instrumentalities in a sinker head, said instrumentalities cooperating in the drawing of stitches by moving in a direction opposite to the stitch drawing movement of the needle, each needle and instrumentation cooperating and functioning independently to draw individual stitches and sub-

stantially complete the drawing of a stitch before the next following needle and instrumentality start the drawing of another stitch, including the step of controlling the timing of each needle and instrumentation which cooperate in the knitting of a stitch in such a manner that the needle will reach its extreme stitch drawing position slightly before the cooperating instrumentality completes its stitch drawing movement in the opposite direction.
